US00D941945S

(12) **United States Design Patent** (10) Patent No.: **US D941,945 S**
(45) Date of Patent: **** Jan. 25, 2022**

(54) **GOLF CLUB HEAD**(71) Applicant: **PARSONS XTREME GOLF, LLC**,
Scottsdale, AZ (US)(72) Inventors: **Michael R. Nicolette**, Scottsdale, AZ
(US); **Bradley D. Schweigert**, Cave
Creek, AZ (US)(73) Assignee: **PARSONS XTREME GOLF, LLC**,
Scottsdale, AZ (US)(**) Term: **15 Years**(21) Appl. No.: **29/740,227**(22) Filed: **Jul. 1, 2020****Related U.S. Application Data**(63) Continuation-in-part of application No. 29/733,572,
filed on May 4, 2020, now abandoned.(51) LOC (13) Cl. **21-02**

(52) U.S. Cl.

USPC ..... **D21/736**(58) **Field of Classification Search**USPC D21/736-746, 759
